UNITED STATES PATENT OFFICE.

LAURENCE DAVIES, OF NEW MALDEN, ENGLAND.

WATER-WASTE PREVENTER.

1,339,690.

Specification of Letters Patent. Patented May 11, 1920.

Application filed May 29, 1919. Serial No. 300,635.

To all whom it may concern:

Be it known that I, LAURENCE DAVIES, subject of the King of Great Britain, residing at 55 Kings avenue, New Malden, in the county of Surrey, England, have invented certain new and useful Improvements in Water-Waste Preventers, of which the following is a specification.

This invention comprises improvements in water waste preventers and particularly to such as comprise a closed flushing tank or cistern.

One object of the invention is to provide a simple and efficient apparatus of this class in which the delivery of water is controlled by a valve which is seated, by the pressure in the tank, on the upper extremity of a tubular part upstanding from the bottom of the tank or cistern.

Another object is to arrange matters so that upon the opening of this valve, the flow of water to the discharge tends to maintain the valve in the open position and the pressure in the tank has only limited access to the space above the valve for effecting the subsequent closing of the latter.

Another object is to provide for the opening of the valve by relieving the pressure above the valve and permitting pressure applied beneath such valve to effect the opening.

Yet another object is to provide a control device for the discharge valve whereby the latter cannot be manually held in the open position, or mechanically fixed therein, the control being exercisable only for starting the flush and being thereafter inoperative until certain conditions are restored by the re-filling of the tank or cistern.

The accompanying drawings forming part of this specification, illustrate, by way of example, two different constructions comprising these improvements, but it is to be understood that the invention is not limited to these constructions as the same may be modified in various ways without departing from the essential features hereinafter described and set out in the claims.

Figure 1 of the drawings is a central vertical section of one construction of closed flushing tank or water waste preventer embodying these improvements in which the discharge valve is mechanically operated.

Fig. 2 is a transverse section on the line II—II of Fig. 1.

Fig. 3 is a central vertical section of an

other construction comprising a control device in the form of a valve adapted for relieving pressure above the discharge valve in order to permit the latter to open.

60

Fig. 4 is a plan of Fig. 3.

Fig. 5 is a plan view of a central chamber and valve seat seen in Fig. 3, the said chamber and seat being turned through about 45° from the position shown in Fig. 3.

65

Fig. 6 is a central vertical section on the line VI—VI— of Fig. 5.

Fig. 7 is a side elevation of the valve casting detached and as seen from the right hand side of Fig. 3.

70

Referring to the construction seen in Figs. 1 and 2, *a* is a closed tank of suitable shape and capacity formed with an aperture *b* at the top and with an aperture *b*¹ at the bottom. The aperture *b* is closed by a cover *c* which may be bolted on, and this cover has a socket portion *f* on its lower side into which is screwed a length of tube *g* extending to the bottom of the tank *a*. The bottom aperture *b*¹ is closed by bolting on a flanged tubular casing *h* to the lower end of which is connected the discharge or flush pipe *i*. In the upper end of the casing *h* is screwed a length of tube *k* of smaller external diameter than the bore of the tube *g*. The tube *k* is disposed within the tube *g* and reaches nearly to the top of the latter, while the tube *g* has its lower end a little above the bottom of the tank *a*, or rather above the depressed portion of the bottom formed by the flange of the chamber *h* covering the aperture *b*¹.

80

The upper end *k*¹ of the tube *k* forms a seating for a valve *l* having the usual winged guide stem *l*¹, a washer *l*² being interposed to give tight closing. The disk of the valve *l* nearly fits within the bore of the tube *g* so as to act like a piston with a leakage between the periphery of the disk and the wall of the tube *g*. The service pipe for filling the tank is connected at *m* and, naturally, the rate of discharge of the tank must be greater than the rate of supply at *m*. The valve *l* may meet a buffer device in opening, in order to prevent shock.

95

The casing *h* is formed with a stuffing box *h*² and with a bearing recess *h*³ for a spindle *n*, a gland being screwed into the stuffing box *h*² to compress a packing *o* on the spindle *n* and thus make a water-tight joint at the place where the spindle *n* emerges from the casing. The spindle *n* has an operating

100

105

110

lever *p* secured to its outer end, and a cam or arm *q* secured to it within the casing *h*. A rod *r* rests upon the lever *q* and is guided centrally within the tube *k* by guide arms or spiders *s* *s*¹ fixed on the rod *r*. The upper end of the rod *r* nearly touches the valve *l* in the inoperative position of the parts.

In operation, suppose the tank to be nearly filled, the pressure due to the supply at *m* acts upon the top of the valve *l* and holds the latter down on its seat. If the lever *p* be depressed, the arm *q* will rise and lift the rod *r* which in turn lifts the valve *l*. The pressure in the tank now forces the water up the tube *g* and over the upper end *k*¹ of the tube *k*, the discharge ensuing being due partly to the pressure and partly to siphonic action, the tube *g* being the short leg and the tube *k* the long leg of the siphon. The pressure or force of the water beneath the valve *l* maintains the latter in the open position so that it is unnecessary to hold down the lever *p* after the flushing has started. As soon as the lower end of the tube *g* is uncovered, or before that according to the weight or loading of the valve *l*, the flushing will cease owing to the valve re-seating itself and the pressure rising in the space above the valve will forcibly hold the latter down on its seat.

The packing *o* is not necessary seeing that, normally, there is no water or pressure in the discharge pipe and that the flow of water is free while the siphon action is taking place.

In the modification seen in Figs. 3 to 7, the tank consists of a cylindrical body 1 welded to a bottom disk 2 having a central perforation 3 in which is fitted the discharge valve casing 4, a flange 5 on the latter being bolted to the bottom disk 2. An annular chamber 6 is formed just within the casing 4 by screwing into the latter a cylindrical partition 7. The partition 7 is tightly screwed down so that its bottom edge, suitably beveled, seats against a flared wall 8 which merges the cylindrical wall of the casing 4 into the spigot 9 for connecting with the discharge or flush pipe 10. The lower portion of the casing 4 is enlarged for the formation of the annular chamber 6 and a flange 11 is formed in the casing in which the partition 7 is screwed. A central and concentric cup 12 is connected or formed in one with the partition 7, an annular passage 13 being left between the cup and partition. Openings 14, Fig. 7, are formed in the lower and enlarged portion of the casing 4 for the passage of water from the tank into the annular chamber 6 and the partition 7 is connected with the cup 12 by several radial passages or tunnels 15 for the passage of water from the annular chamber 6 to the cup 12. The discharge valve 16 is a lift valve seating upon the upper

concentric edges 17 and 18 of the cup 12 and partition 7, this valve 16 being guided by its winged stem 19 in the cup 12. The valve 16 is faced with packing 20 for making a tight seating on the edges 17 and 18 and thereby effectually preventing communication between the cup 12, the space above the valve 16 and the annular space 13 between the cup 12 and partition 7. The top of the casing 4 is closed by a disk or cover 21, so that the space above the valve 16 is an inclosed chamber but a small bore is formed in the casing 4 in any convenient position as for example at 22.

When the tank is connected with the service pipe at 37, it is filled with water under pressure, the said water passing through the openings 14 and filling the annular chamber 6, the radial passages 15 and the cup 12. The water also passes through the bore 22 and fills the space above the valve 16. As the upper surface of the valve 16 so exposed is greater than the area exposed to the pressure in the cup 12 it follows that the valve 16 is held down tightly on its seat. If the pressure in the chamber above the valve 16 be relieved, then the pressure in the cup 12 becomes effective for lifting the valve 16 from its seat and the discharge takes place from the cup 12 over the edge 17, through the passage 13 and so to the discharge pipe 10. As the tank is emptied quicker than it can be filled from the service pipe, a definite quantity for each flushing can be provided for, and after the discharge of this quantity, the valve 16 will reseat itself and as the tank becomes filled and the pressure rises, such pressure will be again effective for keeping the valve 16 on its seat. The closing of the valve 16, of course, will occur when the rush of water from the cup 12 to the discharge has so far diminished as to be unable to keep the valve 16 lifted.

For effecting the relief of the pressure in the chamber above the valve 16, a duct 23 leads from the said chamber to a relief valve device indicated generally by the numeral 24 and incased in a fitting on the tank bottom as shown, or placed in any convenient position and connected with the duct 23 by a suitable length of pipe.

An advantageous relief valve comprises a lift valve 25 having a winged stem 26 for guidance and an annular face for seating on an annular ledge or seating 27 in the casing 28. The last-named is shown screwed direct to a nipple 29 secured in the discharge valve fitting. The relief valve 25 is chambered or cupped and contains a piston 30 the rod or stem of which projects through a hole in the bottom of the cup. The admission to the cup above the piston 30 is by the way of a small bore or capillary hole 31 formed in the top of the valve 130

25 or cover of the cup. A push rod 32 slides in a stuffing box 33 and guide sockets 34 and is formed with a cam-like projection 35 extending just beneath the stem of the piston 30, so that when the rod 32 is pushed in, the cam 35 forces the piston 30 upward.

In operation, the tank 1 being charged with water and the valve 16 held on its seat by the pressure as above described, and the 10 valve 25 being held on its seat owing to the pressure in the duct 23, the pressing inward of the rod 32 causes the cam 35 to raise the piston 30. The rising of the piston 30 at first expels some of the water from the piston 15 chamber through the small hole 31 but the pressure quickly rises in such piston chamber until the effective pressure acting upwardly on the valve 25 is greater than the effective pressure acting downwardly on 20 such valve. The latter then opens, but the piston continues to rise relatively to its chamber either due to the continued raising by its cam of the piston, or to the depression of the valve by the outflow of the water 25 or the weight of the valve 25. The small amount of water flowing past the valve 25 passes away to the closet pan, or other place to be flushed, and the effect is to relieve the pressure above the discharge valve 16, so 30 that the latter opens in the manner above described and the flushing discharge takes place. Upon releasing the push rod 32, the latter may be returned to the outward position by a spring 36 and the relief valve 25 35 re-seats itself but cannot be operated again until the pressure has been re-established for depressing the piston 30 to the bottom of its cylinder or chamber, so as to bring its rod or stem within effective range of the 40 cam 35. The flushing discharge having been started will continue without continued pressure on the rod 32, seeing that the discharge valve will not be re-seated until the full discharge has occurred as above set 45 forth.

It is to be understood that the invention is not limited to the constructions described, as it will be apparent to those familiar with apparatus of this nature that various modifications are possible without departing from the invention. For example, the particular mechanism for operating the relief valve may be modified in various ways and such known equivalents as lever arms, and 50 rotary cams may be substituted for the sliding cam 35. Also, it will be seen that the pressure active upon the valve 16 to close it may be the pressure due to the head of water in the tank, or that head plus the 55 pressure of the supply due to the tank being closed against the atmosphere.

I claim:—

1. A water waste preventer comprising a tank, concentric tubular parts at the discharge orifice of said tank, a discharging

pipe, a discharge valve normally closing communication between the central space inclosed by the inner tube and the annular space inclosed between the two tubes there being communication between the interior 70 of the tank and one of said spaces and between the discharge pipe and the other of said spaces, said valve being maintained on its seat by fluid pressure and, when lifted, being held off its seat by the force of the 75 discharge, and means controlling the rising of said valve from its seat substantially as set forth.

2. A water waste preventer comprising a tank, concentric tubular parts at the discharge orifice of said tank, a discharge valve 80 normally closing communication between the central space inclosed by the inner tube and the annular space inclosed between the two tubes there being communication between the interior 85 of the tank and one of said spaces and between the discharge and the other of said spaces, a chamber inclosing a space above said valve and having a restricted communication with the space in 90 the interior of the tank, said valve being maintained on its seat by fluid pressure and, when lifted, being held off its seat by the force of the discharge, and means controlling the rising of said valve from its seat 95 substantially as set forth.

3. A water waste preventer comprising a tank, an annular valve seating supported above the bottom of said tank and surrounding the discharge orifice of said tank, a second seating similarly supported and surrounding a space in free communication with the water space of said tank, a discharge valve adapted to close on to said 100 seatings, a valve chamber above said seating and having restricted communication with the water space of said tank, a duct leading from said chamber to the exterior of said tank, a pressure relief valve normally closing said duct, and means operative 105 upon said relief valve to open it substantially as set forth.

4. A water waste preventer comprising a closed tank adapted for connection with a pressure supply, an annular valve seating 115 supported above the bottom of said tank and surrounding the discharge orifice thereof, a second seating concentric with the first and similarly supported said second seating surrounding a space in free communication with the interior of said tank, a discharge valve adapted to close on to said 120 seatings, a valve chamber above said seatings and having restricted communication with the interior of said tank, a duct leading from said chamber to the exterior of said tank, a self-closing valve in said duct 125 and operative means adapted for opening said self-closing valve.

5. A water waste preventer comprising a 130

- closed tank adapted for connection with a pressure supply, an annular valve seating supported above the bottom of said tank and surrounding the discharge orifice thereof, a 5 second seating concentric with the first and similarly supported said second seating surrounding a space in free communication with the interior of said tank, a discharge valve adapted to close on to said seatings, a 10 valve chamber inclosing said seatings and said valve and having restricted communication with the interior of said tank, a duct leading from said chamber to the exterior of said tank, a self-closing valve in said duct, operative means adapted for opening said self-closing valve, said operative means comprising an operative connection which is 15 dependent upon normal pressure conditions for its complete operativeness substantially 20 as set forth.
6. A water waste preventer comprising a tank with a discharge orifice in its bottom, a cylindrical wall upstanding around said orifice, a chamber open at its upper end and supported within the space inclosed by said 25 wall, a discharge valve adapted to seat itself upon the upper annular edges of said wall and said central chamber, a valve chamber inclosing said wall, valve and central chamber 30 and having a restricted communication with the interior of said tank, ducts communicating between the interior of said tank and said central chamber, a duct leading from said valve chamber to the exterior of 35 said tank, a pressure relief valve on the last-named duct, and operative means for said pressure relief valve substantially as set forth.
7. A water waste preventer comprising in 40 combination a partially balanced pressure-closed discharge valve, a duct and a relief valve adapted to be operated to relieve through said duct the closing pressure on said discharge valve, a piston in said relief 45 valve adapted to be depressed by the pressure in said duct, and manually operated means having a range for engaging said piston when the latter is depressed by the pressure substantially as set forth.
- 50 8. A water waste preventer comprising in combination a partially balanced pressure-closed discharge valve, a duct and a relief valve adapted to be operated to relieve

through said duct the closing pressure on said discharge valve, a piston chamber 55 formed in said relief valve with a top cover having a capillary opening to said duct, a piston in said chamber having its stem protruding through a bottom opening in the relief valve, and manually operated means 60 adapted for operatively engaging said stem in the depressed condition of said relief valve and piston therein substantially as set forth.

9. Discharge valve fitting for a water 65 waste preventer comprising a valve casing having a valve chamber in its top portion and an annular chamber around its bottom portion there being a restricted opening from the exterior into said top chamber and 70 an unrestricted opening into said annular chamber an annular discharge passage encircled by said annular chamber, a central cup encircled by said passage, ducts communicating between said annular chamber 75 and said central cup, a duct extending from the top chamber to the exterior of the fitting, and a valve adapted to seat and close the openings of said annular passage and said cup substantially as set forth. 80

10. Discharge valve combination for a water waste preventer comprising a valve casing having a valve chamber in its top portion and an annular chamber around its bottom portion there being a restricted 85 opening from the exterior into said top chamber and an unrestricted opening into said annular chamber, an annular discharge passage encircled by said annular chamber, a central cup encircled by said passage, 90 ducts communicating between said annular chamber and said central cup, a relief duct extending from the top chamber to the exterior of the fitting, a valve adapted to seat and close the openings of said annular passage and said cup, a self-seating valve normally closing said relief duct, a piston working in a chamber formed in said self-seating valve said chamber having a restricted opening into said relief duct and said piston having its stem projecting beyond the bottom of said valve and manually operated means adapted for operatively engaging 95 said stem when so projected substantially as set forth. 100

LAURENCE DAVIES.
